UNITED STATES PATENT OFFICE.

JOSHUA M. MORRIS, OF ROCHESTER, NEW YORK, ASSIGNOR TO STANWEAR MANUFACTURING COMPANY, INC., OF ROCHESTER, NEW YORK, A CORPORATION OF NEW YORK.

ENGINE-STARTING MECHANISM.

1,288,649.

Specification of Letters Patent. Patented Dec. 24, 1918.

Application filed June 17, 1913. Serial No. 774,112.

To all whom it may concern:

Be it known that I, JOSHUA M. MORRIS, of Rochester, in the county of Monroe and State of New York, have invented certain 5 new and useful Improvements in Engine-Starting Mechanisms; and I do hereby declare the following to be a full, clear and exact description of the same, reference being had to the accompanying drawings, 10 forming a part of this specification, and to the reference-numerals marked thereon.

My invention relates to an engine starting mechanism, with reference more particularly to devices for starting explosive engines by means of compressed air or other fluid, and it has for its object to provide an improved and novel construction for application to a multi-cylinder engine. A further object of my improvement consists in 15 providing an arrangement whereby the compressed fluid is properly fed to the cylinders of an engine in succession, commencing with the cylinder whose piston is at the upper limit of its stroke, and following thereafter 20 with the other cylinders in regular order until each piston has been actuated by the fluid pressure. A further purpose of my invention resides in an improved arrangement for operating a distributing device which controls the feed of fluid pressure to the 25 cylinders, whereby an initial adjustment may be made so that the position of parts in the distributing device will coincide properly with the position of the pistons in the 30 cylinders. Still a further object of my invention consists in making it possible for the fluid that is used to start the engine to be compressed and stored by the same device that operates to distribute it to the cylinders 35 when starting, the distributing device being geared up with the engine and adapted to be operated as a compressing pump when the engine is running. A further advantage 40 of the invention consists in the employment of automatic pressure controlled devices which operate to start the compressing pump when the pressure in the tank falls below the required level, and also to stop its operation when the pressure is raised sufficiently. To 45 these and other ends the invention consists in certain improvements and combinations of parts, all as will be hereinafter more fully described, the novel features being pointed out in the claims at the end of the specification.

In the drawings:

Figure 1 is a plan view showing a six cylinder engine equipped with a preferred embodiment of the invention;

Fig. 2 is a partial side elevation of the 60 same;

Fig. 3 is a transverse vertical sectional view showing the distributing device and co-operating parts in end elevation;

Fig. 4 is a vertical sectional view of the 65 distributing device with the actuating cam in elevation;

Fig. 5 is a horizontal sectional view of the same on the line 5^a—5^a of Fig. 7;

Fig. 6 is a detail perspective view of one 70 of the bushings employed in the distributing device;

Fig. 7 is a vertical sectional view of the distributing device:

Fig. 8 is a plan view of the same; 75

Fig. 9 is a similar view, a portion being broken away, with the cover plate or top removed, and

Fig. 10 is a detail sectional view on the 80 line 10^a—10^a of Fig. 9.

Similar reference numerals throughout the several figures indicate the same parts.

The arrangement shown in the present application is illustrative of one of several constructions for carrying the invention into 85 effect, which may also be accomplished in other ways, and in the embodiment shown, the engine is designated generally at A and consists of cylinders A², A³, A⁴, A⁵, A⁶ and A⁷ which may be constructed in any 90 approved manner and are provided with suitable pistons and a crank shaft B. C is a receiver or storage tank for the fluid pressure which is supplied to the cylinders of the engine through a distributing device D 95 in a manner which will presently be set forth. The distributing device D has a series of ports from which the pipes a², a³, a⁴, a⁵, a⁶ and a⁷ lead to the respective cylinders of the engine aforementioned. The 100 fluid pressure is supplied to the distributing device from the storage tank C through a pipe c² in which is included a pressure indicator c³ and a check valve c⁴. A turning plug c⁵ may be employed to positively cut 105 off the flow through the pipe c² when this is desired, such valve being opened when the engine is to be started as will appear more clearly hereinafter.

The fluid pressure from the receiver C en- 110

ters the distributing device at the top through the opening d passing thence into the chamber d' from which lead the ports d^2 , d^3 , d^4 , d^5 , d^6 , and d^7 arranged to communicate with the pipes a^2 , a^3 , etc. The distributing device embodies a plurality of movable members which are adapted to close communication between the ports d^2 , d^3 , etc., and the pipes a^2 , a^3 , etc., and to 10 open communication with only one of said pipes at a time, each pipe being successively in communication with its corresponding port in the distributing device through the operation of the movable members which, 15 for this purpose, serve as valves. This I preferably accomplish by the instrumentality of a series of pistons e^2 , e^3 , e^4 , e^5 , e^6 , and e^7 , arranged for reciprocating movement within the bushings d^8 which have 20 openings d^9 in alinement with the ports d^2 , d^3 , etc. Any suitable means may be employed to impart successive reciprocations to the pistons e^2 , e^3 , etc., and this is preferably accomplished by means of a rotary 25 cam f which is mounted on the shaft f^2 and is arranged for engagement with suitable projections on the pistons in the form of anti-friction rollers e^8 . The pistons are cut away, as indicated in Figs. 4 and 7, 30 and the bushings within which the pistons operate are correspondingly cut away to accommodate the cam f . As the latter is rotated, the pistons e^2 , e^3 , etc., are successively raised and lowered, and communication 35 between the ports d^2 , d^3 , etc., and the pipes a^2 , a^3 , etc., is closed except when each piston is at the downward limit of its movement. The cam f is so constructed that one piston is down while the remaining pistons 40 are all raised sufficiently to close their respective ports so that fluid pressure is passing to only one cylinder at a time, this in each instance being the cylinder whose piston is at the upward limit of its stroke and 45 ready to descend. The cam shaft f^2 may be driven in any convenient manner from the crank shaft of the engine, and to this end the latter may be provided with a bevel pinion b in engagement with a similar pinion f^3 which is fixed on the shaft f^4 . The shaft f^4 carries a clutch member f^5 splined thereon, and arranged for coöperation with a corresponding clutch member f^6 carried by the shaft f^2 . The separable clutch members f^5 and f^6 are afforded in order to disconnect the distributing device from the crank shaft for a purpose that will presently appear, and in starting the engine, it is essential that the projections or teeth on 55 the clutch members be in contact with each other so that the position of the piston valves in the distributing device will correspond with the position of the pistons in the cylinders of the engine. For this adjustment, I provide a manually operated

means for turning the cam shaft of the distributing device, whose clutch engages the coöperating clutch member on the shaft f^4 . In the present embodiment, this adjusting mechanism comprises a pulley f^7 mounted 70 on the shaft f^2 , and a similar pulley f^8 mounted in a bracket on the dash board E , the pulley f^8 being provided with a handle f^9 by which it may be turned, and f^{10} is a cable passing around the pulleys f^7 and 75 f^8 . By this means, the cam shaft f^2 can be adjusted until the clutch members are in engagement with each other, whereupon the pressure fluid will pass from the distributing device into the proper pipe leading to 80 the particular cylinder whose piston at such instant is at the upper limit of its stroke, and in the succeeding operations, as the cam shaft turns with the engine shaft, the different ports will be opened to permit the pressure fluid to pass successively to the other cylinders as their pistons reach the upward 85 positions.

After the engine is started, the valve c^6 is closed thereby cutting off the supply of 90 pressure fluid to the distributing device, after which the latter may be employed as a compressor to replenish the supply of pressure fluid in the tank C . In order to accomplish this, the tank C is connected 95 with the distributing device by means of pipes g , g^2 having check valves g^3 arranged therein and connected to the openings g^4 of the distributing device provided in the cover plate H . g^5 is an annular chamber beneath 100 the openings g^4 , said chamber being connected with the interior of the distributing device by means of openings g^6 formed in the plate g^7 . Disposed above said openings g^6 and in the chamber g^5 is an annular ring of rubber, leather, or similar flexible material g^8 above which is disposed a similar annular ring of metal g^9 . The ring g^9 carries a series of vertical pins or projections g^{10} extending through openings in 110 the cover plate H and surrounded by springs g^{11} by which the rings are held yieldably in position directly over the openings g^6 , serving as a check valve therefor when the device is used as a compressor. Under such 115 conditions, the pistons e^2 , e^3 , etc., force the fluid through the openings g^6 and the pipes g , g^2 into the receiver tank. g^{12} is an air inlet communicating with the openings d and provided with a check valve g^{13} . By 120 this construction, each piston e^2 , e^3 , etc., may act as a compressing device to replenish the supply of fluid pressure used in starting the engine. It is desirable that automatic means be provided for stopping the movement of 125 the pistons last referred to when the pressure reaches a certain predetermined point, and to this end I may provide a pressure controlled mechanism for disconnecting the cam shaft f^2 from the engine. This I ac- 130

complish preferably by means of a supplemental pressure chamber h in which is arranged a slidable plunger h^2 controlled by a spring h^3 and mounted on a rod h^4 . The chamber h is connected by means of a pipe h^5 with the tank C, and by a pipe h^6 with the opening d in the top of the distributing device, the object of the last mentioned connection being primarily to prevent waste of any pressure, which is thereby directed into the distributor. h^7 is a valve adapted to be opened and closed by means of a connecting rod or lever h^8 at the outer end of which is a suitable handle h^9 for operating the same. The clutch member f^1 is provided with a shifter h^{10} pivoted at h^{11} and connected at its opposite end with the aforementioned rod h^4 . Thus, when the valve h^7 is closed, the plunger h^2 will be held up, as shown in Fig. 3, and the clutch member disconnected as long as the pressure in the pressure tank or receiver is up to the proper point, and if the pressure drops, the clutch members will be engaged thereby causing the cam shaft f^2 to be operated. This will effect movement of the pistons in the distributing device so as to compress more air which is fed back to the receiver until the pressure is raised to the desired point and the clutch members again automatically disconnected.

In the operation of the parts, when it is desired to start the engine, the valves h^7 and c^5 are opened, thereby bringing the clutch members into operative relation and permitting the fluid pressure to pass to the distributing device. The pulley f^8 is then turned until the projections on the clutch members are engaged, whereby the pressure fluid passes at once to the proper cylinder through its respective port and effects the initial movement of the engine. The consequent turning of the crank shaft imparts movement to the cam shaft f^2 thereby operating the piston valves of the distributing device so as to successively open the ports to the remaining cylinders until the engine is properly started. Thereupon the valve c^5 is closed, as is also the valve h^7 . Following this, the pistons in the distributing device compress the air and charge the receiver until the pressure is raised sufficiently to

lower the clutch member f^5 out of engagement with the clutch member f^6 , after which the parts remain in the position shown until a further operation is desired.

It will be understood that while I have shown a particular embodiment of the invention, I do not limit myself to the precise arrangement or details disclosed herein, but intend to cover by this application any modifications that come within the scope of the claims hereinafter.

I claim as my invention:

1. In an engine starting mechanism, the combination with a fluid pressure supply, of a plurality of cylinders, a distributing device comprising a plurality of reciprocating members adapted to act alternately as valves to permit passage of fluid pressure to the cylinders and as pistons to compress the fluid supply, a rotatable cam in operative engagement with said members, automatically actuated means for operating said cam, and manually operated means for adjusting the position of the cam.

2. In an engine starting mechanism, the combination with a fluid pressure supply, of a plurality of cylinders, and a distributing device embodying a series of movable members, a rotary cam in operative engagement with said movable members, driving mechanism for the cam including a pair of separate clutch members, and manually operated means for adjusting the cam and the corresponding clutch member to bring it into proper relation with the other clutch member when starting.

3. In an engine starting mechanism, the combination with a fluid pressure supply, of a plurality of cylinders, a distributing device comprising a plurality of movable members adapted to supply pressure successively to the different cylinders, a rotatable cam in operative engagement with said members, automatic means for operating said cam, and manually operated means for rotating the cam independently of the aforesaid operating means.

JOSHUA M. MORRIS.
